UNITED STATES PATENT OFFICE

JOSEPH GALAMB, OF DETROIT, MICHIGAN, ASSIGNOR TO FORD MOTOR COMPANY, OF DEARBORN, MICHIGAN, A CORPORATION OF DELAWARE

DOOR LATCH

Original application filed August 15, 1927, Serial No. 212,909. Divided and this application filed August 31, 1929. Serial No. 389,656.

The object of my invention is to provide a door latch of simple, durable and inexpensive construction.

Still a further object of my invention is to provide a door latch specially adapted for use in connection with the doors of an automotive vehicle whereby the door pillars may be of minimum thickness to thereby make the vision from the body greater and whereby the controls for opening the latch may be most conveniently placed.

Still a further object of my invention is to provide a door latch for an automobile body door wherein the door is made from sheet metal and comprises inner and outer panels with the door pillars therebetween whereby the glass channel for the door may rest against the inner surfaces of the door pillar thereby largely decreasing the cross section of the door pillar.

Still a further object of my invention is to provide a door latch wherein the outside door handle may be disposed adjacent to the surface of the door glass and the inside door handle may be disposed at a place spaced very materially from the door pillar and the door latch may be shaped to pass around the edge of the door glass to thereby make the latch construction compact and so that it will not materially increase the cross sectional area of the door pillar.

Still a further object of my invention is to provide a door latch for use in connection with a sheet metal door wherein the latch is formed from a strip of sheet metal which is bent angularly at various points along its length to provide a bridge extending around the edge of the door glass and a lug at either end which may be operated by the adjacent door handle whereby the door latch may be operated from either the inside or the outside of the door, and still it is not necessary to run any parts of the lock directly through the door pillar to

thereby increase the necessary cross sectional area of said pillar.

Still a further object of my invention is to provide in combination with such a latch, an inside door handle, which may be extended to position near the center of the door or to whatever position may be most convenient for the operator to reach.

Still a further object of my invention is to provide in combination with an outside door locking handle for use in connection with my improved lock, a key operated locking member which may prevent turning of the outside door handle without first using a key.

Still a further object of my invention is to provide in connection with such an outside door handle, key operated means for locking the handle from rotary movement and an arrangement in the nature of the keyhole slot connection to prevent the door handle from being withdrawn from the door when it is in such locked position.

With these and other objects in view my invention consists in the arrangement, combination, and construction of the various parts of my improved device as described in the specifications, claimed in the claims and illustrated in the accompanying drawings in which:

Figure 1 shows an elevation of my improved door latch looking along the inside of the door toward the door pillar, the glass channel and glass being removed to better illustrate the construction.

Figure 2 shows a horizontal sectional view through the door and body pillar taken on the line 2—2 of Figure 1, the inside operating handle being shown to better illustrate the construction.

Figure 3 shows a sectional view taken on the line 3—3 of Figure 2.

Figure 4 shows a sectional view taken on the line 4—4 of Figure 1.

Figure 5 shows a sectional view taken on the line 5—5 of Figure 1.

Figure 6 shows a vertical sectional view through the inside door panel adjacent to the place where the inside door handle extends therefrom to better illustrate the position and mounting of said handle.

Figure 7 shows a portion of the inside door panel and remote control rod, the upholstery being removed to better illustrate the construction.

Referring to the accompanying drawings I have used the reference numeral 10 to indicate the outside door panel and reference numeral 11 to indicate the inside door panel. These parts are connected at the free edge of the door by the door pillar 12. This door pillar 12 is recessed near the central part thereof to receive a latch plate 13 which is suitably secured to the pillar as by rivets 14. This latch plate is provided with a recess within the central upper portion thereof through which the door latch 15 may extend. It will be noted that this door latch 15 is formed from a single strip of sheet metal which has its central portion bent upon itself to form an angular latch portion having a pocket or recess on the under side thereof and at the outer end of the latch portion, the strip is bent to form the lug 16. At the inner end of the latch portion proper, of the latch member 15, ears 17 are turned over and provided with aligned openings through which the latch pintle 18 may extend. This latch pintle 18 is fixed in spaced ears 19 which are struck inwardly from the material of the latch plate 13. It will be noted that a portion of the material which is cut out from the latch plate 13 to permit the latch 15 to pass therethrough may be turned up to form these ears 19.

At the outer edge of the latch plate 13 an integral tongue 20 is formed which extends perpendicular to the edge of the latch plate 13 and in substantially horizontal alignment with the latch 15. This tongue 20 forms one of the brackets in which the rollback 21 is journaled, the latter being operated by the outside door handle and operating the outer end of the door latch 15. This rollback 21 is provided with an upwardly extending lug 22 which coacts with the lug 16 of the latch 15 so that the turning of the rollback 21 will move the lug 22 to thereby retract the latch 15. A second bracket 23 forms the journal for the free end of the rollback 21 and is secured to the latch plate 13 by means of a turned in foot 24. This bracket 23 has a portion which is bent upon itself as at 25 to form a door handle retaining member. This door handle retaining member has a square opening 26 therethrough for a purpose which will hereinafter be described.

A spring 27, having a couple of convolutions around the dog 21, has one end thereof

designed to coact with the surface of the latch plate 13 and the opposite end thereof bearing against the lug 22 on the rollback 21 (as will be seen in Figure 5) whereby the intermediate convolutions of this spring 27 may tend to move the rollback 21 to its normal as distinguished from its retracted position. The rollback 21 has a squared opening therethrough designed to receive a square shank 28 on the outside door handle. This shank 28 is provided with an annular channel 29 adjacent to its inner end whereby the squared end of the shank 28 may pass through the squared opening 26 in the retaining member 25 only when the door shank is in its operative position. The normal position of the outside handle when the latch is in normal position is such that the shank will have to be rotated through approximately 45° from normal in order to reach the position in which it can pass through the squared opening 26. This therefore means that the outside door handle can not be withdrawn from the retaining member 25 when the latch is in normal position.

The outside door panel 10 is provided with an opening through which the shank 28 may pass. Adjacent to this opening are a pair of spaced openings designed to receive lugs 30, which are pressed out of a washer 31 which is disposed on the outside of the outside door panel 10 around the shank 28.

This washer 31 is provided with an annular sleeve 32 which extends laterally therefrom on the outside of the outer panel, and it is provided with a notch to receive a key operated bolt 33 mounted in the outside door handle 34. This bolt 33 is designed to be moved into and out of engagement with the notch in the sleeve 32 by a key extended into the outside door handle 34. An escutcheon plate 35 is rotatably but non-slidably mounted on the door handle 34, and is removably secured to the outside door panel 10 by screws 36, whereby said plate may normally support the door handle assembly on the door. This plate also encloses the washer 31 and protects same against unauthorized tampering.

From the construction of the parts just described it will be seen that the bolt 33 may be reciprocated to prevent rotation of the door handle 34 relative to the washer 31. This washer cannot rotate relative to the door panel 10 so long as the lugs 30 extend therethrough, whereby the door handle when locked is held in normal position. The door handle cannot be pulled outwardly to permit the lugs 30 to clear the panel 10 when the door handle is in normal as distinguished from the retracted position due to the engagement of the outer edge of channel 29 with the square opening 26. When locked, therefore, the door handle cannot be rotated or withdrawn and hence

loosening the escutcheon plate at that line has no effect. If it is desired to remove the outside door handle for replacing or repairs, the escutcheon plate is unscrewed, and the handle unlocked, which will permit the door handle to be turned to the position where the squared portion of the shank 28 will pass through the retaining member 25, thereby permitting withdrawal laterally of the entire door-handle assembly.

The key operated lock construction is not herein illustrated as such constructions are all well known in the art and any standard commercial form of the cylinder type may be disposed in the door handle 34 to reciprocate the bolt 33. The washer 31 is rotatably but non-slidably mounted on the door handle within the escutcheon plate 35 by means of a washer 66 and a spring 67 whereby the door handle assembly may be removed or installed by turning the handle 45° and setting or taking out the two screws 36.

A spring 37 has a couple of convolutions passing around the latch pintle 18 and one end thereof bearing against an extension 38 to the latch 15 while the opposite end of the spring bears against the inside door panel 11 at 39. This spring 37 therefore tends to normally urge the latch 15 into its normal or extended position. It will be noted therefore that the latch 15 may move to its retracted position when the door is slammed without affecting the position of the outside door handle as the lug 16 simply moves away from the lug 22 and the latch will be returned to its normal position by spring 37. The latch 15 is provided beyond the extension 38 with the lug 40 which is formed integral therewith.

The inside door panel 11 is provided with a bead or channel 41 which coacts with clips 42 to provide a bearing for a rod 43 which extends along the outside of the inside door panel to operate the door latch from the inside of the door. The end of this rod 43 adjacent to the lug 40 is bent to form a crank 44 whereby rotation of the rod 43 may swing the crank 44 against the lug 40 to thereby retract the latch 15. The remote end of the rod 44 is provided with an arm 45 which is preferably formed integral therewith and which extends through a slot in the adjacent clip 42 so that a handle 46 may be secured thereto. It will be seen that if the handle 46 is grasped adjacent to its free end, pulling thereon away from the outer panel 11 will rotate rod 43 to thereby retract latch 15. It will be noted that this rod 43 may be of any suitable length so that the handle 46 may be placed at the most convenient place for the operator of the car to reach. A spring 47 is designed to coact with the rod 43 to return to the normal position with the arm 45 stopped

against a stop 72 formed integral with the clip 42 and to prevent rattle thereof.

Door latch 15 coacts with an adjustable striker plate 62 which is moved to the desired position within a channel 63 which forms a part of the body pillar 64. Adjustment of the striker plate 62 is accomplished by loosening screw 65 to thereby permit the striker plate 62 to slide along the channel 63 to position to latch the door so that it will not rattle. Tightening screw 65 will then lock the striker plate due to the serrations on the bottom of the plate and the channel 63.

Among the many advantages arising from my improved latch it will be seen that I have provided means whereby the glass channel may rest against the central portion of the door pillar so that the total "blind spot" may be as small as possible.

Still a further advantage results from the use of my improved device in that separate spring means are provided for returning practically all of the parts to normal position so that rattle is largely eliminated.

A further advantage results from the novel and convenient means for preventing removal of the outside door handle when it is locked, and for permitting easy installation or removal of the door handle assembly when it is unlocked.

Still a further advantage results from providing means for mounting the inside door handle whereby it may be extended to the position most convenient for the operator, and whereby the extended inside door handle may be mounted on the door with few additional parts and little change in the panel.

Some changes may be made in the construction and combination and arrangement of my improved device without departing from the spirit of my invention, and it is my intention to cover by my claims such changes as may reasonably be included within the scope thereof.

This application is a division of my pending Serial Number 212,909, filed August 15, 1927.

I claim as my invention:

1. In a door latch, a door having inside and outside panels connected at one edge with a door pillar, a latch pivoted to the door pillar, a horizontal groove formed in the inside panel, an operating rod rotatably mounted in said groove, a crank formed on one end of the operating rod extending through the inside door panel in position to coact with the door latch, and an operating handle secured to the other end of said rod.

2. In a door latch for automobiles, a door formed from sheet material having inside and outside panels connected at one edge with a door pillar, a latch pivoted to the

door pillar, an outside door handle for operating the latch, a horizontal groove formed in the inside door panel, an operating rod rotatably mounted in said groove having a crank extending from one end co-
acting with the latch and a second crank extending from the other end, the rod being of sufficient length that the cranks are spaced a substantial distance apart, and an operating handle on the second mentioned
10 crank.

August 26, 1929.
